THEODORE F. HUSSA, OF MONTCLAIR, NEW JERSEY.

SINGEING APPARATUS.

1,374,375.

Specification of Letters Patent. Patented Apr. 12, 1921.

Application filed January 15, 1918. Serial No. 211,917.

To all whom it may concern:

Be it known that I, THEODORE F. HUSSA, a citizen of the United States, residing at Montclair, in the county of Essex and State 5 of New Jersey, have invented certain new and useful Improvements in Singeing Apparatus, of which the following is a specification, reference being had therein to the accompanying drawings, which form a part 10 thereof.

My invention relates to singeing apparatus and more particularly to such an apparatus particularly adapted for use in the removing of fluff from threads.

15 A singeing apparatus made in accordance with my invention is so constructed as to induce an air current having a very low rate of flow about the singeing element, in a manner to prevent the accumulation of incinerated particles of fluff, removed from the thread, upon or about said element, and at the same time maintain substantially uniform temperature conditions throughout the entire length of the troughed member 20 25 of the singeing element. In order to insure a more rapid and more thorough singeing of the thread, and avoid any tendency of the extinguishment of the flame emanating from the resistance member, this member 30 is inclosed in a manner to direct the air across the top edges of the troughed portion thereof, the inclosing means having air openings so disposed as to prevent the development of air jets which would impinge 35 upon said member in a manner to have a tendency to cool same. The manner of inclosing the resistance member is such as to maintain substantially uniform temperature conditions throughout the entire length 40 45 thereof. It is essential that the trough of the resistance member be arranged with its axis extending substantially vertically, and it is preferable to so arrange the various parts as to have the induced air current, flow counter to the natural draft, a condition 50 tending to temper the air circulated about the resistance member and permit the development of an air current having the desired low rate of flow; and cause this air current to supplement the action of gravity in removing the larger incinerated particles 55 of fluff from adjacent the resistance member.

The invention consists primarily in a singeing apparatus embodying therein a troughed resistance member mounted upon an extended base, and having its axis ex-

tending substantially vertically, a casing inclosing said resistance member having air inlet passages adjacent one end, and extending substantially the full length, of said troughed member, and an air outlet passage adjacent the other end of said member, said casing being so formed as to direct air across the top edges of said troughed member, a conduit communicating with the air outlet 60 65 passage of said casing, and means creating sub-atmospheric pressure in said conduit whereby an induced current of air at a low rate of flow, is created about said element; and in such other novel features of construction and combination of parts, as are hereinafter set forth and described, and more particularly pointed out in the claims hereto appended.

Referring to the drawings:

Figure 1 is a front elevation of a portion of a machine disclosing the essential characteristic of my invention; and

Fig. 2 is a section on the line 2—2 of Fig. 1 upon a larger scale.

Like letters refer to like parts in both views.

In the embodiment of the invention shown in the drawings, I have illustrated only that portion of a thread singeing machine to which my invention relates, the spool supporting and thread rewinding mechanisms included in apparatus of this character, not being related in their functionings, to the singeing elements and their appurtenances.

In the drawings, I have shown at *a* and *b*, the ordinary bus-bars through which the current for making the various singeing elements incandescent, is drawn.

95 The singeing element shown in the drawings, comprises a base *c* of insulating material having mounted thereon and electrically connected with said bus-bars, a troughed resistance member *d*, the base block *c* extending laterally beyond said troughed member.

A plurality of singeing elements are included in a machine, all arranged upon the same horizontal plane, the member *d* on each 105 of these elements being positioned with the axis of the trough extending vertically. Below the various elements is a trunk conduit *e* having extension conduits *f* terminating below each of the elements, the top of the 110 conduits *f* being closed excepting for an opening *f'* in substantial alinement with the

troughed member *d* coöperating therewith. The trunk conduit *e* has mounted therein, or is in communication with, a suitable suction device, as the fan *g*, capable of creating 5 an induced circulation of air at a low rate of flow, throughout the entire apparatus.

Mounted upon each of the extension conduits *f* is a casing *h* of a length to project above the upper end of, and substantially in- 10 close, the sides of said casing extending upon a curve into close proximity to the base block *c*, as shown in the drawings.

The casing *h* is mounted upon the extension conduit *f* by means of a hinge, as *h'*, 15 or in any other manner which will permit the movement of the casing away from the singeing element.

Adjacent the hinge *h'* is an eye *i* through which the thread passes to the rewinding 20 mechanism.

The sides of the casing *h* are spaced away from the block *c* sufficiently to admit air within said plate and about the resistance member *d* for substantially the entire length 25 of said member, the upper end of said casing projecting beyond said member so as to admit air above said member. The curved sides of said plate extend about the opening *f'* in the conduit *f*. By this construction, a 30 continuous current of air having a low rate of flow enters the conduit *f* from within the casing *h* through the opening *f'*, said plate serving to direct the air in a manner to secure the desired operative effect of the flame 35 from the troughed member of the singeing element upon the thread passing through said member.

The extension conduits *f* and the singeing element associated with each, are multiplied 40 in a singeing apparatus to an extent to secure the desired capacity in said apparatus. Each singeing element operates entirely in- 45 dependently of every other element in its functionings, however, the sole variance in the structure of the apparatus made necessary by the use of different numbers of singeing elements, being in the capacity of the trunk conduit *e*, or of the fan *g*, or both.

The operation of the herein described ap- 50 paratus is substantially as follows:—

In threading the apparatus, the casing *h* is moved away from the singeing element, and a thread is passed vertically of the troughed portion of the resistance member 55 and connected with the rewinding mechanism in the usual manner. The circuit to the bus-bars *a* and *b* is then closed bringing the various resistance members *d* to a state of incandescence. The flame from these re- 60 sistance members will remove the fluff from the threads, the particles of incinerated fluff being sufficiently light to have a tendency to float in the air about the singeing element, or to pass upwardly as the result of convec- 65 tion, about the singeing element, particu-

larly when the resistance member has associated therewith an inclosing casing. There would also be a marked tendency of these particles of fluff to be deposited upon the resistance member itself, which would have 70 the effect of fouling this member in a manner to lessen its efficiency.

By creating and maintaining a continuous, induced air current having a low rate of flow, through the casing *h* and substantially axially of the troughed portion of the resistance member *d*, the particles of fluff removed from the thread enter this air current and are carried away from the element thereby, said particles having a natural tendency when first removed from the thread, to fly outwardly of said troughed portion.

By admitting air upon opposite sides of the troughed portion for substantially the full length thereof as well as at one end 85 thereof, I am not only enabled to avoid jets of air which will impinge upon different parts of the resistance member, but am enabled to admit a sufficient volume of air about the element to insure the maintenance 90 of the desired air current, having a slow rate of flow and also to temper the air about the element in a manner to promote combustion and equalize the temperature conditions at all points of the element.

As the air enters the casing through the side and end openings thereof it will have both a vertical and a lateral component of motion which will tend to impart a whirling action thereto, this gentle whirl of air having a tendency to wrap the flame from the resistance member, about the top of the thread passing through the troughed portion and thus thoroughly singe the entire surface of the thread. By arranging the air openings on both sides of the resistance member, opposed currents of air will meet above the trough and have a tendency to carry the discharged particles of fluff away from the thread and the trough. This action 100 is insured by forming the opposite edges of the inclosing casing in an overhung curve, so as to cause the casing itself to give direction to the incoming air.

If air were admitted only at one end of 115 the resistance member, the temperature conditions within the inclosing casing would be different at different points in the length of said member, the greatest temperature being adjacent the opening *f'* through which the extension conduit *f* communicates with the space about the singeing element within said casing. By providing side openings, however, that portion of the volume of air passing through the casing, admitted through the side openings, will tend to reduce the temperature of the air within the casing at all points thereof, in proportion to the normal tendency of this air to become heated. The air admitted nearest the opening *f'*, and consequently 120

having the shortest distance to travel, is admitted at a point where the temperature of the air will be normally at its highest. This prevents the development of excessive temperature about any portion of the resistance member.

The arrangement of parts by which the air current flows counter to a natural draft, has the two-fold advantage of insuring the rapid removal of the particles of incinerated fluff (since this current supplements the action of gravity); and utilizing the products of combustion, which have a normal tendency to rise by passing them along the entire length of the element with a resultant tempering of the volume of incoming air, and the equalization of temperature conditions above referred to.

It is not my intention to limit the invention to the precise details of construction shown in the accompanying drawings, it being apparent that such may be varied without departing from the spirit and scope of the invention.

The essential characteristic of my invention is an apparatus so constructed as to utilize a current of air about the resistance member of the singeing element for the purpose of securing the proper temperature conditions about this element and removing the incinerated particles of fluff without developing an air jet impinging upon any portion of the element, since I have found that such an air jet has the effect of extinguishing the flame from the resistance member, and making it impossible to remove fluff particles from the thread.

Having described the invention what I claim as new and desire to have protected by Letters Patent is:—

1. A singeing apparatus embodying therein an extended base, a troughed resistance member mounted thereon, and having its axis extending substantially vertically, a casing inclosing said resistance member having air inlet passages adjacent one end, and extending substantially the full length, of said troughed member, and an air outlet passage adjacent the other end of said member, said casing being so formed as to direct air across the top edges of said troughed member, a conduit communicating with the air outlet passage of said casing, and means creating sub-atmospheric pressure in said conduit whereby an induced current of air at a low rate of flow, is created about said resistance member.

2. A singeing apparatus embodying therein an extended base, a troughed resistance member mounted thereon, and having its axis extending substantially vertically, a casing extending across said resistance member and having its opposite sides terminating in close proximity to, but spaced away from, said base, said casing being open at

the top and bottom thereof, whereby air inlet passages are formed at one end and for substantially the length of each side of said resistance member, and an air outlet passage is formed at the other end thereof, a conduit communicating with the air outlet passage of said casing, and means creating sub-atmospheric pressure in said conduit whereby an induced current of air at a low rate of flow, is created about said resistance member.

3. A singeing apparatus embodying therein an extended base, a troughed resistance member mounted thereon, having its axis extending substantially vertically, a casing inclosing said resistance member having air inlet passages adjacent the top and extending substantially the full length of each side of said troughed member, and having an open bottom, said casing being so formed as to direct air across the top edges of said troughed member, a conduit communicating with the space within said casing adjacent the bottom thereof, and means creating sub-atmospheric pressure in said conduit whereby an induced current of air at a low rate of flow, is created about said resistance member.

4. A singeing apparatus embodying therein an extended base, a troughed resistance member mounted thereon having its axis extending substantially vertically, a casing extending across said resistance member and having its opposite sides terminating in close proximity to, but spaced away from said base, said casing being open at the top and bottom thereof, whereby air inlet passages are formed at one end and for substantially the length of each side of said resistance member, and an air outlet passage is formed at the other end thereof, a conduit communicating with the air outlet passage of said casing, and means creating sub-atmospheric pressure in said conduit whereby an induced current of air at a low rate of flow, is created about said resistance member.

5. A singeing apparatus embodying therein a trunk conduit having a plurality of extension conduits, each of said extension conduits having associated therewith an extended base, a troughed resistance member mounted thereon and having its axis extending substantially vertically, a casing inclosing said resistance member having air inlet passages adjacent one end and extending substantially the full length of opposite sides of said troughed member, and an air outlet passage adjacent the other end of said member, said casing being so formed as to direct air across the top edges of said troughed member, and an air outlet passage of said casing being in communication with the extension conduit co-operating therewith, and means whereby sub-atmospheric pressure is developed in said trunk conduit.

6. A singeing apparatus embodying there-
in a trunk conduit having a plurality of ex-
tension conduits, each of said extension con-
duits having associated therewith an extended
5 base, a troughed resistance member mounted
on and having its opposite sides terminating
in close proximity to, but spaced away from
said base, said casing being open at the top
and bottom thereof, whereby air inlet pas-
10 sages are formed at one end and for sub-
stantially the length of each side of said re-
sistance member and an air outlet passage
is formed at the other end thereof, said air
outlet passage being in communication with
15 the extension conduit coöperating therewith,
and means whereby sub-atmospheric pres-
sure is developed in said trunk conduit.

7. A singeing apparatus embodying there-
in a trunk conduit having a plurality of
20 extension conduits, each of said extension
conduits having associated therewith an ex-
tended base, a troughed resistance member
having air inlet passages adjacent the top
and extending substantially the full length
25 of each side of said troughed member, and
having an open bottom, said casing being
so formed as to direct air across the top
edges of said troughed member, the exten-
sion conduit coöperating therewith com-
30 municating with the space within said cas-

ing adjacent the bottom thereof, and means
whereby sub-atmospheric pressure is de-
veloped in said trunk conduit.

8. A singeing apparatus embodying there-
in a trunk conduit having a plurality of 35
extension conduits, each of said extension
conduits having associated therewith an ex-
tended base, a troughed resistance member
and having its opposite sides terminating
in close proximity to, but spaced away from, 40
said base, said casing being open at the top
and bottom thereof, whereby air inlet pas-
sages are formed at one end and for sub-
stantially the length of each side of said
resistance member, and an air outlet pas-
45 sage is formed at the other end thereof, the
extension conduit coöperating therewith
communicating with the space within said
casing adjacent the bottom thereof, and
means whereby sub-atmospheric pressure is 50
developed in said trunk conduit.

In witness whereof, I hereunto affix my
signature, in the presence of two subscrib-
ing witnesses, this 19th day of December,
1917.

THEODORE F. HUSSA.
